COMBINED DUPLICATING AND PRINTING MACHINE

John Duke Tyler, Stamford, Conn.

Application July 2, 1941, Serial No. 400,732

12 Claims. (Cl. 101—277)

This invention relates to a printing machine, and more particularly to a printing machine of the class in which a combined duplicating and printing impression may be made simultaneously. A preferred form of my invention will be shown and described in this specification through reference to structure which is shown but not claimed in my copending applications Serial No. 357,555 filed on September 20, 1940 and Serial No. 164,725 filed on September 20, 1937.

Combined duplicating and printing has been accomplished in prior art structures, and in the patent to Mahlstedt No. 1,016,756 granted on February 6, 1912, there is shown a printing machine in which a ribbon duplicator operates in conjunction with printer's type to yield a combined duplicating and printing impression. In Mahlstedt the inking mechanism for the printer's type is located for cooperation with pre-determined end portions of the printing bed, and it is a feature of the machine that the central portion of the bed which carries the ribbon duplicator does not pass into cooperative relation with the inking mechanism. While therefore, Mahlstedt obtains a combined ribbon duplicating and printing impression, his apparatus is inflexible, and it is impossible for him to vary to any considerable extent, if at all, the relation and lengths of the printing and duplicating portion of his impression.

It is a feature of my invention that the duplicated portion of the impression may be located on any part of the printed sheet yielded by my machine by merely placing the duplicating unit in a predetermined position on the type carrying portion of the machine. More specifically, it is a feature of my construction that the duplicating unit of my invention is readily applied to any desired portion of the printing chase or the particular member that carries the type and duplicating unit, and that thereafter the duplicating unit controls parts of the machine, and more particularly the inking mechanism thereof.

An inking assembly which cooperates with type an inking assembly, and with the rollers of the inking assembly preferably of the class adapted to move vertically relatively to the inking assembly, all as set forth in my earlier application Serial No. 164,725. As a feature of my invention, I utilize control segments which are co-extensive and, in effect, integral with the duplicating unit, and which move the inking rollers relatively to the plane of the duplicating unit as the duplicating unit passes under the inking rollers. In this way, the inking rollers are prevented from contacting the duplicating unit, while allowed to contact the

type for inking the type, all of which will now be fully appreciated. It will be understood by those skilled in the art that my invention is adapted for use in a cylindrical type carrying member without fundamental change and that my claims should be so interpreted.

As still a further detailed feature of my invention, the control segments form part of the duplicating unit per se so that as the duplicating unit is placed in assembled relation to the chase, the control segments are automatically positioned for cooperation with the inking rollers to lift them out of contact with the duplicating surface.

While I have thus far indicated that my duplicating unit may be of the ribbon type shown in the Mahlstedt patent, it is possible also to use a stencil duplicating unit such as that shown in the Hommel Patent No. 2,011,363, issued Aug. 13, 1935, or in the Norman Patent No. 1,780,095 issued Oct. 28, 1930. In the drawings and in the specification, I shall refer to a duplicating unit of the stencil type rather than of the ribbon duplicating type merely as a matter of convenience. However, the manner in which the duplicating unit cooperates with the chase and inking rollers is the same, whether it is of the ribbon or stencil type, all of which will be fully appreciated by those skilled in the art.

It may be well to indicate that I consider my invention a broad contribution to the art and that I feel myself entitled to claims of sufficient scope to prevent the utilization by others of my invention in physical forms different from that which I shall hereinafter show and describe. Such different physical forms will readily occur to those skilled in the art.

Referring now to the drawings, Fig. 1 is a vertical section of the printing press shown in my patent application No. 357,555 supra. Fig. 2 is an enlarged view of the inking unit with parts thereof broken away to illustrate the coaction between the inking rollers, the type, and the duplicating unit. Fig. 3 is a partial section taken substantially along lines 3—3 of Fig. 2. Fig. 4 is a plan view of the chase of my printing machine and illustrating a stencil duplicating unit and type assembled relatively thereto. Fig. 5 is a section taken substantially along lines 5—5 of Fig. 1.

Referring now more particularly to the drawings and especially Fig. 1, my printing machine comprises a main frame 10 on which is mounted a motor 11 which through suitable transmission actuates a crank arm 12 which is pivoted at 13 to a crank rod 14. The crank rod 14 is in turn pivoted at 15 to the printing bed 16. It will be

appreciated that the rotation of the motor 11 acts to reciprocate the bed 16, which in Fig. 5 is illustrated as mounted for sliding movement on the bearings 17 and 18 of the main frame 10 through its V-shaped bearing portion 19 and square bearing portion 20.

The chase of the machine is designated in Figs. 4 and 5 by reference numeral 21 and is shown in Fig. 5 mounted on the bed 16 and latched in place by a hook 22 cooperating with the pin 23 of the chase. The type carried in chase 21, when the chase is reciprocated with the printing bed 16, is adapted to cooperate with an impression cylinder 25 and the inking rollers of an inking assembly 26 all as is set forth in my applications supra. While the inking assembly is not per se part of the invention of this application, I deem it best to outline briefly its construction and operation.

The inking assembly 26 is best illustrated in Figs. 1, 2 and 5 to which reference will now be had. There it will be noted that the inking assembly comprises opposed main side plates 27 suitably notched at 28 for cooperation with locator pins 29 mounted on the main frame of the press. Spring pressed latch bolts 30 are mounted on the inking assembly and are controlled by a thumb piece 31. Normally, the latch bolts 30 cooperate with bores 32 of the main side plates 33 of the printing press for latching the inking assembly 26 into the position pre-determined by the locator pins 29 and the notches 28.

The inking assembly may comprise an oscillator roller 34, and a series of inking rollers 35, and the form rollers 36 which are adapted to contact the type 38 carried by the chase 21. As more particularly set forth in my application No. 164,725, the several inking rollers 35 are mounted on shafts 35a while the form rollers are carried on shafts 36a. These shafts 35a and 36a are mounted in bearing blocks 37 relatively to which the shafts rotate with inking rollers 35 and form rollers 36. The bearing blocks 37 are in turn mounted for vertical sliding movement within the arcuate slots 39 formed in the main plates 27 of the inking assembly 26 and are adapted normally to occupy positions in the slots probably best illustrated in Fig. 5 in which the form rollers 36 are shown lying against the type 38 carried in the chase 21. The bearing blocks 37 together with the inking rollers 35 and the form rollers 36 are adapted to move vertically through operation of certain control segments which I have described generally heretofore, and will describe more particularly hereinafter.

In addition, as is set forth in my earlier application No. 164,725, the inking rollers 35 and the form rollers 36, are adapted not only for vertical upward movement, but for a separation relatively to one another, by rotation of the knob 40 and subsequent vertical movement of the cross bar 41 and inside separation plates 42. This arrangement is set forth and claimed in my application Serial No. 164,725 supra.

Referring now more particularly to Fig. 4 the chase 21 is shown as housing a stencil duplicating unit 44 which may be of the type shown in the Hommel and Norman patents referred to supra above. As here shown, it comprises a shallow depressed chamber in which is contained ink which is suitably fed to the under side of the duplicating stencil, all as will be well understood by those skilled in the art. Also, the duplicating

unit 44 may be of the ribbon type as shown in the Mahlstedt patent. The duplicating unit 44 is merely set into the chase 21, and is preferably so formed that there may be secured thereto control segments 45 and 46 which are preferably adapted to overlie the side bars 47 and 48 of the chase 21. Printer's type 38 may also be set into the chase 21, with the type and duplicating unit held in position by suitable furniture 51 and quoins 52.

It will now be readily appreciated that the duplicating unit 44 may be assembled in any longitudinal position relatively to the chase 21 and relatively to the type 38. When the duplicating unit is assembled relatively to the chase 21, the control segments 45 and 46, which are secured directly to the duplicating unit, are automatically adapted for cooperation with the flange rolls 54 secured on each end of each shaft 36a and rotatable with the form rollers 36 as best illustrated in Fig. 3. This cooperation is the same regardless of the selected position of the duplicating unit in the chase, and is completely accurate, as will be understood. Fig. 5 illustrates the flange rolls 54 when the form rollers 36 are in contact with type 38 as when there is no stencil or other duplicating unit 44 within the chase 21. Fig. 3 illustrates the coaction between one of the flange rolls 54 and a control segment 45 of the duplicating unit 44. It will be noted that the control segments coact with the flange rolls 54 to move the form rollers 36 vertically, which movement is possible through the mounting of the form roller shafts 36a in the bearing blocks 37 that are slidable within the arcuate slots 39 of the main plates 27 of the inking assembly 26.

It will now be appreciated that when the duplicating unit 44 is under the form rollers 36, those form rollers are elevated out of the plane of the stencil of the duplicating unit, and that this elevation is dependent merely on the position of the duplicating unit in the chase. Obviously there can be no error on the part of the operator of the machine, since the mere placing of the duplicating unit in the chase automatically determines and controls the operation of the inking rollers. It will be also appreciated that when the duplicating unit leaves a position under the form rollers 36, the form rollers are adapted to drop on to the type 38. Thus in Fig. 2, that form roller 36 at the left of the drawings is shown in contact with the type 38. The flange rolls 54 of that form roller 36 to the right of the type contacting roller 36 are shown in contact with the control segments 45 and 46, and therefore holding the particular form roller 36 out of the plane of the stencil of the duplicating unit 44. It is thought that those skilled in the art will now fully appreciate the significance and operation of my invention and the broad contribution I have made, and which contribution may be utilized in many varying forms by those skilled in the art.

65 I now claim:

1. In a printing machine of the class described, a reciprocating bed, an inking assembly mounted in juxtaposed relation to said bed and having form rollers lying normally in the plane of type carried by said bed whereby to apply ink to said type, means mounting said rollers for movement relatively to said inking assembly and out of the plane of said type, control flanges for said rollers through which said rollers are moved out of the plane of said type, a duplicating unit

adapted for mounting on said bed with its duplicating surface substantially in the plane of said type, and surfaces formed functionally as an integral part of said duplicating unit for contacting said flanges for moving the rollers out of contact with said duplicating surface as said duplicating unit passes under said rollers.

2. In a printing machine of the class described, a reciprocating bed, an inking assembly mounted in juxtaposed relation to said bed and having form rollers lying normally in the plane of type carried by said bed whereby to apply ink to said type over the full effective length of said bed, means mounting said rollers for movement relatively to said inking assembly and out of the plane of said type, control flanges for said rollers through which said rollers are moved out of the plane of said type, a stencil unit adapted for mounting in any one of a series of positions on said bed with its stencil substantially in the plane of said type, and surfaces formed functionally as an integral part of said stencil unit for contacting said flanges in any position in which said stencil unit is placed on said bed for moving the rollers out of contact with said stencil as said stencil passes by said rollers.

3. In a printing machine of the class described, a reciprocating bed, an inking assembly mounted in juxtaposed relation to said bed and having form rollers lying normally in the plane of type carried by said bed whereby to apply ink to said type, means mounting said rollers for movement relatively to said inking assembly and out of the plane of said type, control flanges for said rollers through which said rollers are moved out of the plane of said type, a duplicating unit adapted for mounting on said bed with its duplicating surface substantially in the plane of said type, a frame in which said duplicating unit is mounted, said frame being adapted for insertion in any position on said bed, and control segments formed functionally as an integral part of said frame coextensive longitudinally with the duplicating surface for contacting said flanges to move the rollers out of contact with said duplicating surface as said duplicating surface passes under said rollers, said rollers remaining in contact with the type during that portion of the stroke of the bed when the type is under the said rollers.

4. In a printing machine of the class described, a reciprocating bed, a chase secured on said bed, an inking assembly mounted in juxtaposed relation to said bed and its chase, form rollers in said inking assembly, means mounting said rollers for movement relatively to said inking assembly, said rollers normally rolling on the surface of type mounted in said chase for the full length of said chase, whereby to apply ink to said type, control flanges for said rollers through which said rollers are moved away from the type, a duplicating unit shorter than said chase adapted for mounting in said chase in any one of a series of displaced positions with its duplicating surface lying substantially in the plane of type also mounted in said chase so that a combined printing and duplicating impression will be obtained, and surfaces formed functionally as an integral part of said duplicating unit for contacting said flanges for moving the form rollers out of contact with said duplicating surface as said duplicating surface moves relatively to said rollers.

5. In a printing machine of the class described, a reciprocating bed, a chase secured on said bed, an inking assembly mounted in juxtaposed relation to said bed and its chase, form rollers in said

inking assembly, means mounting said rollers for movement relatively to said inking assembly, said rollers normally rolling on the upper surface of type mounted in said chase for the full length of said chase, whereby to apply ink to said type, control flanges for said rollers through which said rollers are moved off the type, a stencil unit adapted for mounting in any one of a series of displaced positions on said chase with its stencil lying substantially in the plane of type also mounted in said chase so that a combined printing and stenciling impression will be obtained, and surfaces formed as an integral part of said stencil unit for contacting said flanges for moving the form rollers out of contact with said stencil as said stencil passes by said rollers.

6. In a printing machine of the class described, a reciprocating bed, a chase secured on said bed, an inking assembly mounted in juxtaposed relation to said bed and its chase, form rollers in said inking assembly, means mounting said rollers for movement relatively to said inking assembly, said rollers normally rolling on the surface of type mounted in said chase for the full length of said chase, whereby to apply ink to said type, control flanges for said rollers through which said rollers are moved off the type, a stencil carrying frame adapted for mounting in said chase with its stencil lying substantially in the plane of type also mounted in said chase so that a combined printing and stenciling impression will be obtained, and control segments forming an integral part of said stencil unit frame coextensive longitudinally with the stencil for contacting said flanges for lifting the rollers out of contact with said stencil as said stencil passes by said rollers, said rollers remaining in contact with the type during that portion of the stroke of the bed when the type is under the said rollers.

7. In a printing machine of the class described, a reciprocating bed, a chase secured on said bed, an inking assembly mounted in superimposed relation to said bed and its chase, form rollers in said inking assembly, means mounting said rollers for vertical movement relatively to said inking assembly, said rollers normally rolling on the upper surface of type mounted in said chase for the full length of said chase, whereby to apply ink to said type, control flanges for said rollers positioned at the ends thereof and through which said rollers are lifted off the type, a duplicating unit carrying frame shorter than said chase and of such width as to fit in any position longitudinal of said chase while leaving room for the positioning of type in said chase, the duplicating surface of said duplicating unit lying substantially in the plane of the type so that a combined printing and duplicating impression is obtained, control segments formed as an integral part of said duplicating unit frame coextensive longitudinally with said duplicating surface and overlying the sides of said chase, said segments contacting said flanges for lifting the rollers out of contact with said duplicating surface as said duplicating surface passes under said rollers, said rollers remaining in contact with the type during that portion of the stroke of the bed when the type is under the said rollers.

8. In a printing machine of the class described, a reciprocating bed, a chase secured on said bed, and having longitudinal side bars lying in juxtaposed relation to the longitudinal edges of said bed, an inking assembly mounted in superimposed relation to said bed and its chase, form rollers in said inking assembly, means mounting said

rollers for vertical movement relatively to said inking assembly, said rollers normally rolling on the upper surface of type mounted in said chase for the full length of said chase, whereby to apply ink to said type, control flanges for said rollers positioned at the ends thereof and through which said rollers are lifted off the type, a duplicating unit adapted for mounting in said chase with its duplicating surface lying substantially in the plane of type also mounted in said chase so that a combined printing and duplicating impression will be obtained, and longitudinal control segments forming an integral part of said duplicating unit and overlying the side bars of said chase for contacting the flanges of said rollers for lifting the rollers out of contact with said duplicating surface as said duplicating surface passes under said rollers.

9. In a printing machine of the class described, a reciprocating bed, a chase secured on said bed, and having longitudinal side bars lying in juxtaposed relation to the longitudinal edges of said bed, an inking assembly mounted in superimposed relation to said bed and its chase, form rollers in said inking assembly, means mounting said rollers for vertical movement relatively to said inking assembly, said rollers normally rolling on the upper surface of type mounted in said chase for the full length of said chase, whereby to apply ink to said type, control flanges for said rollers positioned at the ends thereof and through which said rollers are lifted off the type, a duplicating unit shorter than said chase adapted for mounting in said chase between the longitudinal side bars of said chase and in any predetermined longitudinal position in said chase and with its duplicating surface lying substantially in the plane of type also mounted in said chase so that a combined printing and duplicating impression will be obtained, and longitudinal control segments forming an integral part of said duplicating unit and overlying the side bars of said chase when said duplicating unit is placed in said chase said segments for contacting the flanges of said rollers for lifting the rollers out of contact with said duplicating surface as said duplicating surface passes under said rollers.

10. In a printing machine of the class described, a chase, a duplicating unit for the said machine comprising a main body adapted to fit

in any one of a series of displaced positions on said chase, a flange secured as an integral part of said duplicating unit at one side of said duplicating unit and parallel to the direction of movement of said duplicating unit with said chase in said printing machine, said flange having a surface at least coextensive in length with the duplicating portion of said duplicating unit and adapted to actuate control mechanism of said printing machine for preventing the contact of parts of the printing machine with the duplicating portion of said duplicating unit.

11. In a printing machine of the class described, inking rolls, control means for said inking rolls adapted to position said rolls into and out of the printing plane, a chase adapted to carry type and a duplicating unit, a duplicating unit for said chase adapted to be positioned in any one of a series of displaced positions on said chase, a flange secured as an integral part of said duplicating unit at one side of said duplicating unit and parallel to the direction of movement of said duplicating unit with said chase in said printing machine and at least coextensive with the duplicating portion of said duplicating unit to be contacted during the printing operation, said flange having a surface adapted to actuate said control mechanism of said inking rolls for preventing the contact of said inking rolls with the duplicating portion of said duplicating unit.

12. In a printing machine of the class described, a reciprocating bed, an inking assembly mounted in juxtaposed relation to said bed and having form rollers lying normally in the plane of type carried by said bed whereby to apply ink to said type, means mounting said rollers for movement relatively to said inking assembly and out of the plane of said type, control means for said rollers through which said rollers are moved out of the plane of said type, a duplicating unit adapted for mounting on said bed with its duplicating surface substantially in the plane of said type, and surfaces formed functionally as an integral part of said duplicating unit for contacting said control means for effecting the movement of the rollers out of contact with said duplicating surface as said duplicating unit passes under said rollers.
